UNITED STATES PATENT OFFICE.

ALEXANDER EDWIN HUBBELL, OF MILFORD, MICHIGAN.

COMBINED BLOTTER-HOLDER AND HAND-REST.

1,115,432.

Specification of Letters Patent. Patented Oct. 27, 1914.

Application filed October 18, 1913. Serial No. 795,882.

To all whom it may concern:

Be it known that I, ALEXANDER EDWIN HUBBELL, a citizen of the United States, and a resident of Milford, in the county of Oak-
5 land and State of Michigan, have invented a Combined Blotter-Holder and Hand-Rest, of which the following is a specification.

My invention is a hand-rest provided with means for holding an ordinary blotter and 10 particularly adapted for use of bookkeepers but also serviceable for general use of writers.

The invention is embodied in the construction, arrangement, and combination of parts 15 hereinafter described, and illustrated in the accompanying drawing, in which—

Figure 1 is a plan or top view of the device. Fig. 2 is a bottom view, including a portion of a blotter or blotting sheet. 20 Figs. 3 and 4 are cross sections on the lines 3—3 and 4—4, respectively, of Fig. 1. Fig. 5 is a cross section on the line 5—5 of Fig. 2.

The numeral 1 indicates the body of the device which is a flat, thin, oblong plate, 25 preferably constructed of celluloid and having its edge beveled on the upper side. One of the longer bevels is graduated in inches to adapt the device to serve as a rule or measure. The plate 1 is provided on the 30 under side with corner pockets 2 adapted to receive the corners of a blotter or blotting-sheet 3, and in the middle of the length of the plate 1 the latter is provided with ribs 4 extending lengthwise of the plate. 35 The pockets 2 are formed by means of ribs 5 arranged at a right angle—see Fig. 2—and a thin triangular sheet of celluloid or some equivalent material, which is secured to the ribs by glue or some other suitable 40 adhesive substance. The sides of the ribs which are adjacent to the longer sides of the plate 1 are in alinement with the intermediate or mid-length ribs 4 and the three are located a short distance from the side edges 45 of the plate 1.

The ribs 4 and the pockets 5 serve to support the plate 1 above the surface of a ledger or other book which requires to be ruled, and they also serve as stops which come in contact with the bottom edges of a book when 50 the hand-rest is applied thereto to form an extension of the page or writing surface. In other words, when the device is so applied, its edge overlies the edge of the sheet 55 to be ruled, and the ribs 4 and 5 come in contact with the lower edge of the sheet.

It will be seen that, in order to apply the blotter or blotting-sheet 3 to the plate 1, as indicated in several figures, it is bowed lengthwise and its corners then inserted in 60 the pockets 2. The distance between the middle ribs 4 is exactly the same as the width of the blotter 3, and, in order to adapt the ribs to engage the side edges of the blotter and thus hold its middle portion flat on 65 the plate 1, I provide the inner sides of the ribs with longitudinal grooves, as will be understood by reference to Fig. 5. In other words, by the construction specified, the ribs 70 4 engage with, or bite, the side edges of the blotter, so that it is not liable to bend or bow at the middle of its length.

It will be further seen that, by the construction and combination of parts described, I produce a device which is particularly adapted to serve as a hand-rest for bookkeepers as well as for writers in general and at the same time adapted to serve most efficiently as a holder for a blotter which may be very conveniently used. The 80 device is also adapted to serve as a ruler, by reason of the fact that the parts or devices which hold the blotter in place serve also as means for supporting the plate with its edge above the surface to be ruled and also 85 as means for keeping the plate in due position when it is applied as an extension of a ledger or other book in which writing is to be done.

It will be perceived that by providing the 90 plate 1 with a series of ribs spaced widely apart longitudinally of the plate, the elasticity of the latter is not impaired, as would be the case to a considerable degree if the ribs were continuous or extended the whole 95 length of the plate.

The ruler possesses the desired flexibility to permit its bending in its use for blotting purposes.

The availability of the device for advertising purposes also increases its value.

From the drawing and the foregoing description, it will be noticed that I present a very useful device wherein the elements by their action upon one another perform additional functions and accomplish additional effects.

What I claim is:

1. A combined hand-rest and blotter-holder consisting of a thin elastic plate having its underside provided with corner pockets for receiving a blotter and with

lengthwise ribs arranged intermediately of the pockets and adjacent to the side edges of the plate, the inner sides of such ribs being provided with grooves for engaging the edges of a blotter, as described.

2. A combined hand-rest and blotter-holder consisting of a thin elastic plate having its underside provided with corner pockets formed of ribs arranged at right angles to each other and a thin cap or sheet

secured upon said ribs, and a second set of ribs arranged intermediately of the pockets and adjacent to the side edges of the plate to serve as side-guards for a blotter, as described.

ALEXANDER EDWIN HUBBELL.
